UNITED STATES PATENT OFFICE.

MELCHIOR MILLER, OF LE MARS, IOWA.

ADJUSTABLE TOOL.

1,103,808.

Specification of Letters Patent. Patented July 14, 1914.

Application filed May 19, 1913. Serial No. 768,682.

To all whom it may concern:

Be it known that I, MELCHIOR MILLER, a citizen of the United States, and a resident of Le Mars, in the county of Plymouth and State of Iowa, have invented certain new and useful Improvements in Adjustable Tools, of which the following is a specification, reference being had to the accompanying drawings, forming a part of this specification.

The object of my invention is to improve the construction and operation of that class of tools as used in grinding valves and valve seats, to the end that a tool may be provided that can be readily adjusted to fit into the key sockets of any ordinary valve.

With these and other objects in view the present invention consists in the combination and arrangement of parts as will be hereinafter more fully described and finally pointed out in the appended claims, it being further understood that changes in the specific structure shown and described may be made within the scope of the claims without departing from the spirit of the invention.

In the accompanying drawings forming a part of this specification, and in which like numerals of reference indicate similar parts in the several views: Figure 1 shows an elevational view of an adjustable tool embodying my invention. Fig. 2 is an edge view of Fig. 1.

The valves as well as the valve seats as used in explosive engines, in course of time become coated with a deposit commonly called "soot," so that the valve will not accurately fit upon the seat. In order to remove the deposit, it is simply necessary to cover the bearing surface of the valve with a suitable abrasive material such as emery, and rotate the valve in order to grind off the "soot" and insure a close fit of the valve and seat. Valves, and especially those employed in gasoline engines are conventionally provided with two sockets located upon opposite sides of the center of the valve, these sockets being arranged to receive the key bosses of a suitable tool to the tang of which is secured a suitable rotating member as a brace. The size of the valve determines the size of the lug sockets, as well as the distance these sockets are from the center of the valve, and in grinding the valves of an ordinary engine, usually

three separate valve-engaging tools are necessary.

In my present invention however, I provide a valve tool including two members which are secured in adjusted relation, so that the tool can be used in engaging the boss sockets of a small valve, as well as those of a large valve, in the operation of grinding the valve.

In carrying out the aim of my invention, I provide a tang 1, which has its chuck-engaging end 2, tapered and squared, so that the end 2, will securely fit within a chuck or square tool socket. Intermediate of its ends the tang 1 is provided with the enlargement 3, while the remaining end is in the form of an enlarged flat head 4, from the end and near one corner of which extends a key boss 5, which is preferably cylindrical.

Laterally extending from the enlargement 3, is the pivot lug 6, which is arranged for co-action with the eye 7, which is pivotally held upon the pivot lug. This eye 7 forms a part of the stub tang 8, which has the enlarged flat head 9, provided with the transversely extending slot 10 and from the end and one corner of which extends the key boss 13, the key bosses 5 and 13 extending in parallel spaced relation.

The head 4 is provided with two threaded screw openings arranged to receive a set screw 12, which passes through the slot 10, and the head of which is adapted to bind upon the head 9, to securely hold the two enlarged flat heads 4 and 9 in adjustable relation.

In the use of the tool, the screw 12 is loosened and the fixed key boss 5 is inserted in one of the boss openings within the valve to be ground, while the other and adjustable key boss 13 is arranged to fit into the opposite boss socket within the valve. The key bosses 5 and 13 having been properly adjusted, the screw 12 is tightened to connect the heads 4 and 9. The tool can then be rotated in the operation of grinding the valve. When a large or small valve is to be ground, it is simply necessary to loosen the screw 12 and readjust the key bosses 5 and 13.

The tool is simple and inexpensive in construction, and both durable and efficient in operation, and the adjustment of the stub tang can be effected with ease, accuracy and despatch.

Having thus described my said invention what I claim as new and desire to secure by U. S. Letters Patent is:

A tool of the character described comprising a tang having a flat enlarged head from one end of which extends a key boss and which has a laterally extending pivot lug intermediate of its ends a threaded opening being located within the head, in combination with a stub tang at one end having an eye arranged to engage said lug and at the other end a flat enlarged slotted head ar-

ranged to slide over said first mentioned head with a key lug extending from the end thereof said lugs extending in parallel spaced relation and a set screw passing through said slot and threading into said threaded opening, all arranged as and in the manner set forth.

MELCHIOR MILLER.
